UNITED STATES PATENT OFFICE.

CHARLES H. NORTON, OF WORCESTER, MASSACHUSETTS, ASSIGNOR TO NORTON
GRINDING COMPANY, OF WORCESTER, MASSACHUSETTS, A CORPORATION OF
MASSACHUSETTS.

DRIVING MECHANISM FOR GRINDING-MACHINES.

1,161,957.

Specification of Letters Patent. Patented Nov. 30, 1915.

Original application filed June 6, 1913, Serial No. 772,055. Divided and this application filed July 22, 1914.
Serial No. 852,389.

To all whom it may concern:

Be it known that I, CHARLES H. NORTON, a citizen of the United States, residing at Worcester, in the county of Worcester and 5 State of Massachusetts, have invented a new and useful Driving Mechanism for Grinding-Machines, of which the following is a specification.

This invention relates to a machine for 10 grinding surfaces of rotation, especially cylindrical surfaces, and contains matter divided out of my application on a cylindrical grinding machine, filed June 6, 1913, Serial No. 772,055.

15 The principal objects of the invention are to provide a machine of this character of a simple construction in comparison with the kind of work that it accomplishes and capable of being fully controlled and manipulated by an operator in a comparatively simple way, the machine being self-contained not only with respect to the power shaft but also with respect to the tight and loose pulley so that no overhead counter 20 shaft is required and the shaft can be conveniently driven by a motor, or by a belt coming from above or below. The shipper mechanism for moving the belt to and from the tight and loose pulley is also self-contained 25 in the machine with the operating handle in convenient position upon the front thereof.

Other features relate to an improved speed changing device, and to a novel way 30 of connecting the power shaft with the work drive head.

The invention also involves improvements in combinations and parts and details of construction as will appear hereinafter.

40 Reference is to be had to the accompanying drawings, in which—

Figure 1 is a front elevation of a machine constructed in accordance with this invention; Fig. 2 is an end elevation thereof; 45 Fig. 3 is an elevation of the other end; and Fig. 4 is a rear view.

The machine is shown as comprising a main casting or base A on which operates a sliding table B mounted in longitudinal 50 ways on the top of the base. There is also a

wheel slide C operating in transverse ways toward and from the sliding table which is designed to support the work.

The machine receives its power from a main driving belt 8 (Figs. 2 and 4), passing 55 around a pair of tight and loose pulleys 9 on the main shaft 10 which is carried on the rear of the machine. A shipper handle 11 on the front of the machine is mounted on a horizontally extending rod 11^a to the rear 60 end of which is secured the belt shifter 12. On the main shaft 10 there is mounted a pulley 13 which, by means of a belt 14 and a pulley 14^a, is effective to rotate a cone pulley 15 supported on a stud in one end of 65 a lever 15^b pivoted at its other end to the base A. A second cone pulley 15^a is mounted on a shaft 16 supported in fixed bearings on the base A and driven from the cone pulley 15 by means of a belt 15^b. 70

A belt shifting device of special construction is provided for moving the belt 15^b from step to step upon the cones. This device comprises a sliding block 500 adapted to be moved longitudinally upon a rail 501 75 by means of a handle 502. The block is secured in adjusted position by a spring latch which may be released by the latch handle 503. A horizontally extending support 504 (Fig. 3) is bolted to the block 500 and has 80 pivoted thereto a pair of belt shifting guides 505 and 506. The lower guide 505 is pivotally mounted upon a stud 507 secured to the support 504 and is normally pressed against a stop 508 by a spiral spring 509 concentric 85 with the stud 507. The guide 506 is similarly mounted upon a stud 510 and is provided with a stop and spring corresponding to the stop 508 and the spring 509 but so arranged that the guide 506 will normally be 90 moved in a direction opposite to the movement of the guide 505. The yielding arms herein described are so arranged that the guides will positively move the belt toward the higher step as it approaches either of the 95 pulleys, but will yield upon the other run, allowing the belt to remain in its previous position until it has been shifted on the approaching side. By this device I am enabled quickly to shift a belt upon a pair of 100

cone pulleys without manual manipulation of the belt. The lower cone pulley 15 is mounted upon a stud in the end of a pivoted arm 15^c and is thus enabled to yield upwardly as the belt is being shifted from step to step.

The shaft 16 is suitably connected by devices, not shown in this application, to move the work table B longitudinally. The mechanism by which this movement is accomplished is fully shown in the parent application, to which reference is made for a full description. The hand-wheel 28 constitutes means for moving the table B manually.

15 As is well understood, the sliding table B carries the work, which is to be fed forward and back, and which is also rotated on its own axis. For this purpose the table is provided with a head-stock 85 and a tail-stock 20 86 similar to those in use on lathes, which need not be herein described in detail. The work is rotated by means of bevel gears 98 (Fig. 4) connected with the shaft 10 by the clutch 37, and operating a telescopic shaft 25 99 connected by spiral gears 100 (Fig. 2) with a shaft 101. From this latter shaft a belt drives a cone pulley 102 (Fig. 4) and a belt from this pulley drives a pulley 103 (Fig. 2) on the work spindle 104.

30 For the purpose of rotating the grinding wheel, the shaft 10 is provided with a pulley 118 (Fig. 4) which, through a belt 119 passing over an idler and tightener 120, operates a shaft 121. On this shaft is a pulley 122 carrying a belt 123, which constitutes means for rotating the wheel shaft 126 and the grinding wheel E. A tightener pulley 124 is pressed upon the belt 123 by a weight 125 for which a tension spring may 35 be substituted if desired.

40 The several driving and driven pulleys upon the main power shaft together with the gears and clutches mounted thereon are entirely inclosed within the base or within 45 guard plates and casings fixed to the base.

I have thus provided an improved and simplified driving mechanism for a grinding machine, in the use of which a single operator has full and convenient control of 50 the machine.

55 Although I have illustrated and described only a single embodiment of the invention, I am aware of the fact that modifications can be made therein by any person skilled in the art without departing from the scope of the invention as expressed in the claims. Therefore I do not wish to be limited in these respects, but

What I do claim is:—

60 1. A grinding machine having in combination a base, a grinding wheel and shaft supported thereon, and means to drive said wheel shaft, said means comprising a power shaft supported in bearings on said base,

tight and loose pulleys on said shaft, a belt 65 for rotating said pulleys and shaft, a belt shipper mounted on said base for controlling said belt, and connections from said shipper extending through the base to an operating handle on the front thereof. 70

2. A grinding machine having in combination a base, a grinding wheel and shaft supported thereon, and means to drive said wheel shaft, said means comprising a power shaft supported in bearings on said base, a 75 driven pulley on said power shaft for rotating the shaft, a driving pulley on said shaft for driving the wheel shaft, a second driving pulley on said power shaft for driving the work table feed, a gear loose on said power shaft for driving the mechanism for 80 rotating the work, a clutch on said power shaft for connecting said gear to said power shaft, and covering plates fixed to said base and inclosing said pulleys and said gear. 85

3. A grinding machine having in combination a base, a grinding wheel and shaft supported thereon, means to drive said wheel shaft including a power shaft supported in bearings on said base, a longitudinally movable work table having a rotatable spindle thereon, an intermediate shaft mounted on said table and connected to rotate said spindle by variable speed connections between said intermediate shaft and 90 said spindle, and connections from said power shaft to said intermediate shaft, said last named connections including a telescoping shaft, a pair of beveled gears for driving said telescoping shaft from said power 95 shaft, and a pair of spiral gears for driving said intermediate shaft from said telescoping shaft.

4. A grinding machine having in combination a base, a grinding wheel and shaft 105 supported thereon, means to drive said wheel shaft including a power shaft mounted on said base, a work table, a rotatable spindle on said table having a pulley secured thereto, an intermediate shaft mounted on the 110 table and having a driving pulley and a cone pulley thereon, a belt connecting said driving pulley to the pulley on the spindle, a second intermediate shaft on said table having a cone pulley, and a spiral gear thereon, 115 a belt connecting said cone pulleys, a second spiral gear meshing with the first named gear and movable longitudinally with said table, and telescoping connections from said second spiral gear to said power shaft. 120

5. A grinding machine having in combination a base, a grinding wheel and shaft supported thereon, means for driving said wheel shaft, a work table mounted on said base and longitudinally movable thereon, and means to move said work table, said latter means including a cone pulley supported on a fixed bearing, a second cone pulley sup-

ported on a movable bearing, a belt connecting said pulleys, and devices to shift the belt from one step to another on said pulleys, said devices comprising a sliding block, 5 a pair of guides yieldingly mounted thereon, and a stop for each guide limiting its movement in one direction.

In testimony whereof I have hereunto set my hand, in the presence of two subscribing witnesses.

CHARLES H. NORTON.
